his attorney.

UNITED STATES PATENT OFFICE.

JESSE E. KEPPEL, OF ST. LOUIS, MISSOURI, ASSIGNOR TO VULCAN VALVE COMPANY, OF ST. LOUIS, MISSOURI, A CORPORATION OF MISSOURI.

VALVE.

1,212,362.

Specification of Letters Patent. Patented Jan. 16, 1917.

Application filed February 17, 1916. Serial No. 78,819.

To all whom it may concern:

Be it known that I, JESSE E. KEPPEL, a citizen of the United States, residing in the city of St. Louis and State of Missouri, have invented new and useful Improvements 5 in Valves, of which the following is a specification.

This invention relates to fluid pressure valves, and has special reference to an improved valve for use in connection with 10 pneumatic tires of vehicles.

Valves as now generally used in this connection are, relatively speaking, quite complicated, and it is therefore one of the principal objects of my invention to provide a 15 valve which shall be characterized by extreme simplicity in construction.

A further object of the invention is to provide a valve of the character indicated 20 which shall be sensitive and reliable in operation, and, as an incident to its simple construction, one which will not be liable to get out of order, and which will therefore have the maximum life.

25 The invention is illustrated in the accompanying drawing, in which—

Figure 1 is a longitudinal sectional view through my improved valve and the casing in which it is mounted; Fig. 2 is a view in 30 elevation of my improved valve removed from the casing; and Fig. 3 is a longitudinal sectional view of the lower portion of the valve member, showing it in open position.

35 Referring now to the drawing, the numeral 1 indicates a valve casing of a well-known type which is provided with an air duct 2 and reduced portion 3, said reduced portion 3 being provided with interior and exterior screw-threads, and the portion of 40 the air duct immediately below said reduced portion of the casing being enlarged to provide a chamber 4 to accommodate a valve 5. This valve is in the form of a tubular shell, 45 and at its outer end is provided with a non-circular portion 6, and below said non-circular portion with a shoulder 7 against which is seated a gasket 8. Below said shoulder the tubular shell is provided with a 50 screw-threaded reduced portion 9, below said screw-threaded portion with a further reduced cylindrical portion 10, and below this portion with a still further reduced cylindrical portion 11, the end of which 55 forms the valve-seat. The numeral 12 in-

dicates a hollow valve member which is slidably mounted on the reduced portion 11 and receives the lower end thereof, being closed at its outer end. The reduced portion 11 is provided with an annular shoulder 13 located slightly above the lower end affording the valve-seat, and the upper edge portion of the valve member 12 is swaged or turned inward, as indicated at 14, so that in the outward movement of the valve member 12 60 said swaged portion will engage the shoulder 13 and prevent the valve member from falling off of the valve shell. In the bottom of the valve member 12 I place a disk or gasket 15 which is preferably of rubber, and 65 against which the end 13 of the shell is adapted to seat to afford a secure closure against the passage of air through said shell.

The valve member 12 is provided in its side walls with apertures 16 which, when its end is in engagement with the disk or gasket 15 will be located above the said end. When, under the pressure of inflation, the valve member 12 is forced downward, the apertures 16 are carried below the shoulder 75 13 and preferably below the end of the valve-shell, permitting the air to pass out of said apertures into the chamber 4 and through the duct 2 to the tire. For deflating the tire I secure to the bottom of the 80 valve member 12 on the inner side thereof a stem 17 which extends upward through the bore of the tubular shell to the end thereof provided with the nut or non-circular portion 6. By the use of a suitable implement, 85 as will be understood, the deflating stem 17 may be pressed downward, thereby moving the valve member downward to uncover the apertures 16 and permit the air to flow in from the tire through said apertures and 90 through the valve-shell to the outer air. It will be understood, of course, that the wall of the chamber 4 does not closely embrace the valve member 12, but affords a sufficient 95 space surrounding the valve member to permit the passage of air through the valve in either direction as above described.

I claim:

1. In a valve mechanism of the class described, a valve comprising a tubular shell 105 adapted to be secured in a casing, a hollow valve member mounted to slide on the lower end of said shell, and having a side wall with an aperture, and a closed end, a gasket supported on said closed end, the lower end of 110

said tubular member providing a valve seat adapted to form a sealing contact with said gasket, and means for limiting the opening movement of said valve member when said aperture is beyond the end of said shell to open communication through the said wall of said valve member and through the end of said shell.

2. In a valve mechanism of the class described, a valve comprising a tubular shell adapted to be secured in a casing, a hollow valve member slidably secured on the lower end of said shell and having a side wall with an aperture, and a closed end, a gasket supported on said closed end, the lower end of said shell providing a valve-seat adapted to form a sealing contact with said gasket, a deflating stem secured to the closed end of said valve member and extending upward through said shell, and means for limiting the opening movement of the said valve member when said aperture is beyond the end of said shell to open communication through the side wall of said valve member and through the end of said shell.

3. In valve mechanism of the class described, a valve comprising a tubular shell adapted to be secured in a casing and provided near its lower end with an annular shoulder, a hollow valve-member slidably mounted on the lower end of said shell and

having a side wall with an aperture, a closed outer end and a turned-in inner end for engaging said shoulder to limit the opening movement of said valve-member when the 35 said aperture is below said shoulder, a gasket supported on said closed end, the lower end of said shell providing a valve-seat adapted to form sealing contact with said gasket, and a deflating stem secured to the closed end 40 of said valve-member and extending upward through said shell.

4. In a valve mechanism of the class described, a tubular shell adapted to be secured in a casing, a hollow valve member slidably secured on the lower end of said shell, and having a side wall with an aperture, and a closed end, a gasket supported on said closed end, said tubular shell having an annular shoulder engaging said valve member, the lower end of said tubular member providing a valve seat adapted to form a sealing contact with said gasket, and means for limiting the opening movement of said valve member when said aperture is beyond said shoulder to open communication through the said 50 wall of said valve member and through the end of said shell.

In testimony whereof, I have hereunto set my hand.

JESSE E. KEPPEL.
